JET PUMP

Clarence G. Wrentmore, Detroit, Mich.; Margaret M. Wrentmore, special administratrix of Clarence G. Wrentmore, deceased

Application June 3, 1932, Serial No. 615,159

8 Claims. (Cl. 302—15)

My invention relates to an improvement in jet pumps and more particularly to such a pump adapted for use in connection with a hydraulic excavating apparatus and the like.

5 Jet pumps heretofore have been used in connection with various apparatus and consist of a device in which a mass of fluid, gas or liquid may be forced under high pressure and velocity into a mass of fluid having a lower pressure and velocity, causing the two masses to mingle into one, the total energy in which is the sum of the total of the energy in the two original masses.

Prior to my invention it has been a customary practice to inject a mass of fluid, gas or liquid under high pressure and velocity into the mass of fluid of lower pressure and velocity through the medium of a solid jet shot into a pipe at or near its center, or an annular jet at its perimeter. Under either of these conditions the difference 20 in velocity of the small high-pressure jet and the larger induced suction stream causes a rolling motion within the fluid mass, which cuts down the efficiency of such devices. The intensity and range of this relative motion between 25 the particles of the fluid passing through the pump determine the magnitude of the losses of energy and so the loss of efficiency of the pump.

It is, therefore, an object of my present invention to provide a jet pump in which the amount 30 and range of the turbulence from the jet is decreased.

It is a further object of my present invention to provide a jet pump in which the mixture of the high speed and the low speed fluid is facilitated and the entire mass reduced to a uniform 35 velocity within a shorter time and at a shorter range than in jet pumps of conventional design.

These and various other objects, features of 40 arrangement, construction and operation, are plainly shown and described and will be best understood by reference to the accompanying drawing, in which:

Fig. 1 is a longitudinal section through a jet 45 pump embodying my invention;

Fig. 2 is a section taken on the line A—A of Fig. 1;

Fig. 3 is a section taken on the line B—B of Fig. 1;

50 Figs. 4 and 5 are diagrammatic sketches showing two jets meeting and merging into a single stream;

Fig. 6 is a diagrammatic sketch showing several jets meeting and merging into a series of 55 radial blades.

Similar reference characters refer to similar parts throughout the several views.

A device embodying my invention as shown in Fig. 1 may be best understood by a consideration of the diagrammatic sketches shown in Figs. 4, 5 and 6.

Referring to Fig. 4, if two jets of fluid *g*—*g* be so directed that they meet, the two jets will merge into a blade *h*, the blade *h* being generally fan shaped in contour, as shown in Fig. 5, the form and direction of the blade *h* depending upon the form and direction of the streams *g* and *g*. If, however, the jets *g* and *g* be equal and symmetrically placed in the same plane, the plane of the blade *h* will bisect the angle between *g* and *g* and lie perpendicularly to the plane of *g*—*g*.

If more than two jets be brought symmetrically together on a central line, as shown in Fig. 6, the jets *i* will merge into a set of diverging blades 20 *k*, whose planes bisect the dihedral angles between the jets *i*. This phenomenon of jet action is utilized in a pump embodying my invention, as shown in Figs. 1, 2 and 3. As there shown, a flanged outer casing *d* is provided with an inferior chamber *a*, through which the high pressure fluid is brought.

A suction tube *b*, having an outer casing *e*, extends into the chamber *a* to a point adjacent the discharge tube *c*, having a casing *f*, which also 30 extends into the chamber *a*. A small clearance *n* is provided between the end of the suction tube *b* and the adjacent end of the discharge tube *c* sufficient to permit fluid to flow from the chamber *a* around the suction tube *b* in the 35 form of a ring, the inner surface of which corresponds to the outer surface of the end of the suction tube *b* and whose outer surface corresponds to the inner surface of the end of the discharge tube *c*. Some of the fluid under pressure passes from the chamber *a* through a plurality of slots *m*. The said slots *m* are equally displaced about the periphery of the end of the suction tube *b* adjacent the end of the discharge tube *c*, and the fluid from the chamber *a* passes 40 through the slots *m* in the form of a plurality of jets which meet at the center of the suction tube *b*. In the annular opening *n* and the slots *m* the high pressure fluid enters the tubes *b* and *c* in a diagonal direction, having a component 45 along the tube larger than the radial component.

The operation of a device embodying my invention is as follows: Fluid under low pressure passes through the suction tube *b* to the discharge tube *c*, and fluid from the chamber *a*, 55

moving at a higher velocity and under a higher pressure than the fluid contained between *b* and *c*, is forced through the opening *n* in the form of a peripheral ring and also passes through the 5 slots *m* in the form of a plurality of radial blades.

By the provision of a plurality of slots *m* equally displaced about the periphery of the suction tube *b*, the jet action occurring within the tube *b* is similar to that shown in Fig. 6 except 10 that the provision of six slots *m*, as shown in Figs. 1 and 3, will cause a correspondingly larger number of radial blades of fluid than those shown in Fig. 6 resulting from the use of but four jets.

15 A jet pump constructed in accordance with my invention will give a jet in which the extent and range of turbulence is considerably less than in conventional types of jets, and by the decreasing of the amount and range of the turbulence I have found that the efficiency of the entire pump is greatly increased.

20 I also have found that a jet constructed in accordance with my invention will produce a higher vacuum than any of the conventional forms 25 of jets with which I am familiar. It also has been found that a jet pump embodying my invention when used for gravel or other gritty material, tends to keep the abrasive substances in the fluid suspended in the fluid in such a manner as to 30 reduce the scour on the surface of the discharge pipe *c*. It also has been found that a jet pump embodying my invention may be used successfully 35 on a straight run of pipe as a booster pump.

40 While I have illustrated and described one embodiment of my invention, it is apparent that various changes and modifications may be made without departing from the spirit of my invention, and I do not wish to be limited to the precise details of construction as herein set forth, but desire to avail myself of all changes within the scope of the appended claims.

Having thus described my invention, what I 45 claim is new and desire to secure by Letters Patent of the United States is:

1. A jet pump including an outer casing having a chamber therein, a suction tube extending through said casing to a point within said chamber, a discharge tube extending through said casing and within said chamber to a point adjacent the end of said suction tube, and means extending through said suction tube and adapted to provide a plurality of high velocity jets so placed within said suction tube adjacent the end thereof, as to form a plurality of intersecting 50 blades of high velocity fluid within said suction tube.

2. A jet pump including an outer casing having a chamber therein, a suction tube extending through said casing to a point within said chamber, a discharge tube extending through said casing and within said chamber to a point adjacent the end of said suction tube, and means adjacent the end of said suction tube to provide a plurality of high velocity jets within said suction tube and including a plurality of slots extending through the casing of said suction tube at points 55 equally spaced about the perimeter thereof, in such a manner that streams of high velocity fluid passing through said jets will meet and form a plurality of intersecting blades of high velocity fluid within said suction tube.

3. A jet pump including an outer casing having a chamber therein, and having means to limit the amount and range of turbulence in said 60 chamber, and including a suction tube extending through said casing to a point within said chamber, a discharge tube extending through said casing and within said chamber to a point adjacent the end of said suction tube, and means to con-

ting through said casing to a point within said chamber, a discharge tube extending through said casing and within said chamber to a point adjacent the end of said suction tube, and means extending through said suction tube and adapted to provide a plurality of high velocity jets so placed within said suction tube adjacent the end thereof as to provide a plurality of intersecting blades of high velocity fluid within said suction tube. 10

4. A jet pump including an outer casing having a chamber therein, and having means to limit the amount and range of turbulence in said chamber, and including a suction tube extending through said casing to a point within said chamber, a discharge tube extending through said casing and within said chamber to a point adjacent the end of said suction tube, and means adjacent the end of said suction tube to provide a plurality of high velocity jets within said suction tube and including a plurality of slots extending through the casing of said suction tube at points equally spaced about the perimeter thereof and adapted to direct high velocity fluid passing therethrough to form a plurality of intersecting blades of such high velocity fluid. 15

5. A jet pump including an outer casing having a chamber therein, a suction tube extending through said casing to a point within said chamber, a discharge tube extending through said casing and within said chamber to a point adjacent the end of said suction tube, and means to convey a fluid under pressure between said suction tube and said discharge tube and to discharge said fluid as an annularly extending band 20 between said suction tube and said discharge tube, and means adjacent the end of said suction tube to provide a plurality of high velocity jets within said suction tube and including a plurality of slots extending through the casing 25 of said suction tube at points equally spaced about the perimeter thereof and adapted to direct high velocity fluid passing therethrough to form a plurality of intersecting blades of such high velocity fluid. 30

6. A jet pump including an outer casing having a chamber therein, a suction tube extending through said casing to a point within said chamber, a discharge tube extending through said casing and within said chamber to a point adjacent the end of said suction tube, means to convey a fluid under pressure between said suction tube and said discharge tube and to discharge said fluid as an annularly extending band 35 between said suction tube and said discharge tube, and means extending through said suction tube and adapted to provide a plurality of high velocity jets within said suction tube adjacent the end thereof and adapted to direct high velocity fluid passing therethrough to form a plurality of intersecting blades of such high velocity fluid. 45

7. A jet pump including an outer casing having a chamber therein, and having means to limit the amount and range of turbulence in said 50 chamber, and including a suction tube extending through said casing to a point within said chamber, a discharge tube extending through said casing and within said chamber to a point adjacent the end of said suction tube, and means to convey a fluid under pressure between said suction tube and said discharge tube and to discharge said fluid as an annularly extending band 55 between said suction tube and said discharge tube, and means extending through said suction tube and

and adapted to provide a plurality of high velocity jets within said suction tube adjacent the end thereof and adapted to direct high velocity fluid passing therethrough to form a plurality of intersecting blades of such high velocity fluid.

5 8. A jet pump including an outer casing having a chamber therein, and having means to limit the amount and range of turbulence in said chamber, and including a suction tube extending through said casing to a point within said chamber, a discharge tube extending through said casing and within said chamber to a point adjacent the end of said suction tube, means to convey a fluid under pressure between said suc-

tion tube and said discharge tube and to discharge said fluid as an annularly extending band between said suction tube and said discharge tube, and means adjacent the end of said suction tube to provide a plurality of high velocity jets 5 within said suction tube and including a plurality of slots extending through the casing of said suction tube at points equally spaced about the perimeter thereof and adapted to direct high velocity fluid passing therethrough to form a 10 plurality of intersecting blades of such high velocity fluid.
